(57) **CLAIM**

The ornamental design for a storage container, as shown and described.

DESCRIPTION

FIG. 1 is a top, front, right-side perspective view of a storage container showing the new design;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is an enlarged view of the area marked "9" in FIG. 1;

FIG. 10 is an enlarged view of the area marked "10" in FIG. 2; and,

FIG. 11 is an enlarged view of the area marked "11" in FIG. 7.

The dashed broken lines depict portions of the storage container that form no part of the claimed design. The dot-dash broken lines encircling portions of the storage container in FIGS. 1, 2, and 7 and illustrated in enlarged views in FIGS. 9-11 form no part of the claimed design.

1 Claim, 11 Drawing Sheets
